ROTARY TYPE FILING AND ABRADING APPLIANCE

Preston M. Hall, Silver Spring, Md.

Application December 23, 1957, Serial No. 704,720

9 Claims. (Cl. 132—73.6)

This invention relates to an electrically operated appliance having a rotary type abrading and filing member associated therewith which can be used for the purpose of filing finger nails, toe nails, hard skin protuberances, and for other filing purposes.

The primary object of this invention is to provide an electrically operated appliance adapted to be used in the hand of an operator and having associated therewith a rotary abrading disc or member which can be used for the purpose of abrading and filing such objects as finger nails.

A further object of this invention is the provision of an abrading and filing head for attachment to rotary types of electrical appliances, such as safety razors, and which has associated therewith one or more readily detachable abrading and filing discs or members which can be safely and efficiently used for filing such objects as finger nails, toe nails, etc.

Other objects and advantages of this invention will be apparent during the course of the following detailed description.

In the accompanying drawing, forming a part of this specification, and wherein similar reference characters designate corresponding parts throughout the several views:

Figure 1 is a perspective view showing the improved appliance in the hand of a user, ready to be used for abrading and filing purposes.

Figure 2 is an enlarged fragmentary cross sectional view taken substantially on the line 2—2 of Figure 1, showing abrading and filing discs and means for the support and drive of the same.

Figure 3 is a plan view of the abrading and filing head with its guard cap removed.

Figure 4 is a transverse cross sectional view taken through the abrading and filing head of Figure 3, substantially on the line 4—4 of Figure 3.

Figure 5 is an exploded view showing the related parts of the improved abrading and filing head adapted for attachment to a rotary type electric appliance, such as a safety razor casing.

In the drawing, wherein for the purpose of illustration is shown only a preferred embodiment of the invention, the letter A may generally designate the improved abrading and filing head, adapted for attachment to rotary type of electrical appliances B, such as safety razors.

The rotary type electrical appliance upon which the improved abrading and filing head is adapted for detachable connection preferably comprises a housing 10 receiving therein an electrical motor (not shown) portions 11 of which are shown extended upwardly in the neck 12 of the housing 10. The latter is of elongated oval shape and at one reduced end is adapted to receive a plug and cord attachment 15 for connection to an electrical circuit. The electrical motor has associated therewith drive shafts 16 and 17, both of which may rotate in the same direction, although they may be oppositely given if the electric appliance B is provided with gearing

for such purpose. The shafts 16 and 17 extend upwardly above the top margin of the neck 12 of the casing 10 and at their upper ends have ends 16^a and 17^a of polygonal cross section. It is within contemplation of this invention to provide a rotary type electrical appliance having merely a single shaft for driving a single rotary abrading and filing member of the head, if so desired.

Referring to the abrading and filing head A, the same includes a main casing or support frame 20 having a lower outwardly flared skirt 21 adapted to fit externally over the neck 12 of the appliance B, and upwardly therefrom having the inset collar 23 which may be marginally beaded at 24 at the top thereof. A top wall 25 may be integrally connected as part of the casing 20, located in a plane below the bead 24 and attached thereto. This wall 25 may be provided with a pair of circular openings 27 and 28 therein, which are shown of rather large diameter in the drawing, but which may be reduced for the purpose for which this invention is adapted. These openings 27 and 28 are separated by a bridging portion 29 of the wall 25. The portion 29 has transverse openings 30 and 31 therein for receiving attaching screws, to be subsequently described.

Preferably there are provided upper and lower elongated plastic plates or discs 35 and 36 respectively which engage over and under the wall 25, in the relationship of parts shown in Figures 2 and 4, and which are clamped in this position by means of the bolts or screws to be subsequently described. These plates or discs 35 and 36 are provided with small openings 38 therethrough to receive the ends of the drive shafts 16 and 17 for free rotation therein. It is to be noted that the top plate 35 rests in the recess created by the bead 24 upon the casing portion 20, and the polygonal shaped keying ends 16^a and 17^a of the drive shafts project above this plate.

Rotary type filing or abrading discs 40 and 41 are provided. They are preferably circular in plan view and centrally are provided with polygonal openings 42 adapted to receive the squared ends of the shafts 16 and 17 for keying them thereto. The compositions of the replaceable filing and abrading discs may vary. They may be sand or emery coated paper or plastic, with the abrasive material being on the upper surfaces thereof and the under surfaces being smooth, since the discs are adapted to rest upon the top surface of the plastic plate 35; the latter furnishing a support for receiving pressure which is applied upon the discs 40 and 41 incident to abrading use.

The means for holding the head assembled in the form above described comprises a holding and guide plate 50 preferably of some highly polished metal although the same may be formed of any material. At its ends plate 50 is provided with circular openings 51 and 52 for receiving the projecting keying ends 16^a and 17^a of the drive shafts 16 and 17. At the opposite sides thereof the plate 50 is provided with depending screw threaded bolt shanks 54, the same having flanged spacer heads 55 which may be soldered or otherwise secured to the laterally extending ears at the sides of the plate 50, as shown in the drawing. These screw threaded shanks 54 are adapted to extend transversely through openings 57 provided in the top plastic plate or disc 35; through the openings 30 and 31 of the casing 20, and through circular openings 58 provided in the lower disc or plate 36. The lower ends of the shanks 54 are adapted to receive nuts 59 engageable against the under surface of the plate or disc 36 for the clamping of the plates 35 and 36 to the wall 25, and likewise for the spaced clamping of the holding and guide plate 50 above the abrading discs 40 and 41. It is to be noted that the abrading surfaces of the discs 40 and 41 are spaced from the under surface of the plate 50, as shown in Figures 2 and 4, and thus do not contact any

part of the detachable abrading and filing head A. The plate 50 is so shaped that a large segmental portion of each of the discs 40 and 41 is upwardly exposed for filing purposes, and the edging 60 at the ends of the plate 50 may be arcuated to furnish a lateral support for the finger nail, either in resting relation thereon or as a guide if it is adapted to rock the finger during filing of the nail, and the fleshy tip of the finger may rest upon top of plate 50.

It is preferred to provide a transparent plastic guard cap 70 for slipping over the inset top portion 23 of the casing portion 20 of the head. This is shown in full lines in Figure 5 and in dot and dash lines in Figures 2 and 4. It furnishes a protection and guard for the head and prevents loss of the filing discs.

The use of the improved abrading and filing head will be apparent from the foregoing. While it has been shown as adaptable for use with the motor part of an electric razor, it is within contemplation of the invention to use the rotary filing portions of this invention in connection with other types of electrically driven appliances. It will be noted that the entire head A is removable from the casing 10 of the electrical appliance, so that it may be replaced with a cutting or clipping head of a conventional razor in event the appliance is needed for use as a shaver.

The improved head A is small, compact and the parts are firmly and securely attached together, but they may be readily disassembled merely by removing the nuts 59 from the screw threaded shanks 54.

New discs 40 and 41 may be replaced since they may be laterally slipped from beneath the plate 50 when the head is removed from the motor casing.

It is within contemplation of this invention to make the discs 40 and 41 reversible. That is, both sides may be provided with abrading material, but in such event a felt or other type protector will be provided for the underside of the disc in order to prevent abrading action upon the plate 35 as an incident of pressure applied during filing.

Various changes in the size, shape and arrangement of parts may be made to the form of invention herein shown and described, without departing from the spirit of the invention or scope of the claims.

I claim:

1. An abrading and filing head for attachment to rotary type electrical appliances having an upwardly extending drive shaft, comprising an inverted cupped supporting casing for attachment to the electric appliance having a top wall provided with an opening through which said shaft is adapted to extend in freely rotatable relation therein and in projecting relation above said wall, a holding and guard plate detachably mounted upon said top wall having means spacing the under surface thereof from the upper surface of the top wall and itself having an opening therein aligning with the opening of the top wall to freely rotatably receive the drive shaft, a replaceable abrasive disc having a keying opening therein adapted to receive said shaft and which opening aligns with the openings in said top wall and plate and which has a thickness whereby to rest upon the top wall with its abrasive surface facing upward and spaced from the under surface of the holding and guard plate.

2. A device as described in claim 1 in which a top cap is provided detachably connected to said casing and covering said holding plate and disc.

3. In an abrading and filing head for attachment to

rotary type electrical appliances having a drive shaft, the combination of an inverted cupped casing having a top wall provided with an opening therein, a plate mounted upon the top wall having a smaller opening therein aligning with the opening of the top wall for receiving the drive shaft of an electric appliance, a removable flat abrading disc having a keying opening centrally therein aligning with the openings in said plate and top wall, and a guard plate removably attached to the top wall of the casing having a plate portion with an opening therein aligning with the openings in the disc, plate and top wall for receiving therein the drive shaft of an electric appliance, the under surface of said guard plate being spaced from the top abrading surface of the disc and partially covering the abrading surface of said disc and leaving exposed a portion of said abrading surface of the disc for filing purposes.

4. In a rotary electrical filing and abrading appliance the combination of a housing having an electrical motor therein and a neck portion, the electrical motor having a drive shaft protruding from the neck portion, and a removable abrading and filing head for the neck portion comprising an inverted cupped casing detachably connected to the neck of said housing having a top wall provided with a passageway therethrough for receiving the outer end of the drive shaft in projecting relation, and a flat rotary type abrading disc provided with an opening keyed upon the projected end of the shaft for rotation by the latter.

5. An appliance as described in claim 4 in which a guard plate is connected to the casing in spaced relation above the top of a portion of the abrading surface of said disc.

6. An appliance as described in claim 5 in which a removable cap is detachably connected upon the top of the casing for sealing the disc and top of the casing therein.

7. In a rotary electric abrading and filing appliance the combination of a supporting housing having an electric motor provided with dual rotary drive shafts projecting therefrom and located in spaced relation, a removable cap mounted upon the casing having a top wall structure provided with openings into which the ends of the drive shafts project, a pair of rotary abrading discs having openings therein receiving in keyed relation therewith the projecting ends of said shafts to locate said discs in the same plane upon the top wall structure of said cap.

8. An appliance as described in claim 7 in which a guard plate is fixedly connected to the top wall structure over adjacent portions of said discs with its under surface spaced from the top abrading surfaces of said discs, the last mentioned plate leaving upwardly facing exposed portions upon each of said discs for abrading and filing purposes.

9. An appliance as described in claim 8 in which a cover cap is provided detachably connected over the top of the plate to seal the discs therein.
